(57) **CLAIM**

The ornamental design for a bottle, substantially as shown and described.

DESCRIPTION

FIG. 1 is a front elevational view of a bottle showing my new design, the rear, right side, and left side elevational views being substantially identical;

FIG. 2 is a top plan view thereof;

FIG. 3 is a bottom plan view thereof; and,

FIG. 4 is a bottom perspective view thereof.

The dashed lines merely represent the top of the bottle and the thickness of the claimed design and form no part of the claimed design. The top of the bottle and the thickness of the bottle are not claimed as features of the bottle.
